HOLDER FOR SHOE ORNAMENTS

Filed Oct. 15, 1928

Inventor:
Maurice Goldstein,

Maurice Goldstein

Att'y.

UNITED STATES PATENT OFFICE

MAURICE GOLDSTEIN, OF PHILADELPHIA, PENNSYLVANIA, ASSIGNOR TO FRANCO-AMERICAN SHOE ORNAMENT COMPANY, OF PHILADELPHIA, PENNSYLVANIA, A CORPORATION OF PENNSYLVANIA

HOLDER FOR SHOE ORNAMENTS

Application filed October 15, 1928. Serial No. 312,628.

My invention relates to certain improvements in holders for shoe ornaments and more particularly has reference to a support for buckles of plain or fanciful design worn 5 on women's slippers, pumps, and like footwear.

It is an object of my invention to provide a holder or support for ornamental shoe buckles which will hold the buckle upon a 10 slipper or pump firmly and free from lateral or vertical displacement.

It is a further object of my invention to provide a shoe buckle holder in the nature of a clasp or clamp which enables the buckle 15 to be quickly and easily attached to and removed from the shoe, the entire holding device being neatly concealed behind the buckle and retained out of view.

Another object of my invention resides in 20 the provision of a holder which is adaptable for use with all sizes and styles of buckles and footwear of the character referred to and having a wide range of interchangeability with respect to buckles and shoes.

In the case of buckle holders now commonly in use, it is necessary by virtue of their construction to stitch or sew the holder to the shoe. This is frequently a tedious operation and does not permit of ready attachment and 25 removal of the buckle holder from the shoe. It is therefore a still further object of my invention to provide a buckle holder or support which necessitates no stitching or sewing but which holds the buckle in position on the shoe 30 by a simple clamping operation, thus enabling both the buckle and the holder to be more quickly and easily attached to and removed from the shoe.

It is a still further object of my invention 35 to provide a device of the character indicated which by a simple and single operation firmly engages the shoe and also the buckle to hold the latter in fixed position and free from displacement in any direction.

Still another object of my invention resides in the provision of a holder or support 40 for shoe buckles which is simple and inexpensive in manufacture and construction, involving a minimum of parts, and which satisfies its purpose in an efficient manner.

With the foregoing objects in view and such others as may hereinafter appear, my invention will be more particularly pointed out in connection with the accompanying drawing forming a part of this specification 55 and showing a preferred embodiment of my invention to which, however, the invention is by no means limited as various changes and modifications may be made therein without departing from the spirit and scope of the 60 invention as defined in the appended claims.

In the drawing, wherein similar reference characters indicate corresponding structural elements in the different views:

Fig. 1 is a view showing my new device 65 supporting an ornamental buckle upon a slipper;

Fig. 2 is a plan view of a metal blank from 70 which the entire device, except for the clamp lever, is formed;

Fig. 3 is a side elevation of my improved 75 holder in open position;

Fig. 4 is a front elevation;

Fig. 5 is a sectional view on the line A—A 80 of Fig. 4 and showing the device in operative 75 engagement with a buckle and shoe upper; and

Fig. 6 is a perspective view of the clamp 85 lever.

Referring more particularly to the drawing, the complete device A is designed for 90 the purpose of holding and supporting an ornamental buckle B upon the upper marginal edge of the front portion of a shoe C, conventionally shown in Fig. 1. Such ornamental buckles are usually formed upon a curved surface and it will readily be seen that when the buckle B is so formed the holding device A will be hidden from view behind the buckle. In the drawing the buckle B has 95 been shown as lying in a vertical plane for the purpose of more clearly illustrating the invention. As a means for attachment, buckles are now manufactured with a back bar D affixed to the rear face thereof.

Except for a clamp lever forming part of my device, the entire holder is manufactured 100 from a single blank of sheet metal stamped out as shown in Fig. 2. The device comprises a front portion 1 which preferably, but

not necessarily, is provided with a groove 2 of sufficient width to receive the back bar D of a buckle. Projections 3, 3 are stamped out of the front portion along the same vertical edge thereof and extend across groove 2. A slit 4 is stamped out of the front portion and is positioned between the projections on the opposite side of the groove. The lower end of the front portion is bent rearwardly to form 10 a clamp member 5, curved downwardly, as shown, to conform with the outer marginal edge of a shoe. The side portions 6 are bent rearwardly of the front portion and are perforated as at 7 for reception of the pintles 8 15 of clamp lever 9.

Extension 10 of the upper end of front portion 1 is bent backwardly and downwardly between side portions 6 as shown in Figs. 3 and 5 and flares outwardly toward its lower 20 end. The extension 10 terminates in a clamp member 11 which is curved in parallelism to clamp member 5. The clamp members 5 and 11 are spaced apart sufficiently to snugly receive the upper front part of a shoe and a neat 25 fit is obtained by virtue of the curvature of these members. Prongs 12 may conveniently be stamped out of the clamp member 11 to provide further grasp upon the shoe. If desired, a strengthening rib 13 may be formed 30 in the flared section of extension 10. Approximately midway on one edge of extension 10 is formed an inwardly directed tongue 14 which is positioned immediately behind slit 4 in front portion 1. Tongue 14 is of such 35 length that when the holder is in the open position of Fig. 3 it does not project materially through the slit but when the device has been closed by movement of extension 10 toward front portion 1, the tongue will project a 40 short distance through the slit for a purpose hereinafter described.

As stated, a clamp lever 9 is pivotally supported in perforations 7 of side portions 6 by 45 the pintles 8, its pivoted end being bent upwardly as shown at 15 for exerting pressure on extension 10 and its exposed end being also turned upwardly. An indent 16 is struck out of the exposed end providing 50 prongs 17, the indent being of sufficient width to engage back bar D of the buckle. The prongs 17 are bent slightly as shown in order 55 to clasp upon the top of front portion 1 to thereby hold the device in closed position.

In use, the clamp lever being in open position, the back bar D of the buckle is slipped 55 beneath projections 3, 3 and into groove 2. The upper marginal edge of the front portion of the shoe is next inserted between clamp members 5 and 11 and clamp lever 9 swung 60 upwardly and the bent prongs 17 clasped over the upper edge of vertical portion 1. By this single operation it will be seen that extension 10, as well as clamp member 11, is pushed forward to simultaneously grasp the shoe between clamp members 5 and 11 and to 65

force tongue 14 through slit 4. Tongue 14 projecting through slit 4 and a short distance beyond front portion 1 acts as a stop to lock the back bar D in the groove and to prevent lateral movement of the back bar. Prongs 70 17 of the clamp lever additionally engage the back bar thus providing further locking means for preventing relative movement between the back bar and holder. Prongs 12, 75 engaging the underside of the shoe, provide a more effective grip on the latter and augment the gripping action of clamp members 5 and 11. To remove the buckle from the shoe it is only necessary to release clamp lever 9 and slip the shoe out of the clamps. The back 80 bar is then free to slide out from under projections 3, 3 and a buckle of different ornamental design may be substituted.

From the foregoing it will be seen that I have devised a holder or support for shoe buckles which is simple in operation and construction, inexpensive in manufacture, being formed essentially from a single blank of metal, and which effectively performs its desired function. The device is adaptable to 85 practically all designs and sizes of buckles and shoes and permits of ready attachment and removal inasmuch as it need not be sewed or otherwise permanently affixed to the shoe. 90

Although I have herein shown and described a preferred form of my invention, it is to be expressly understood that the invention is not limited thereto as various changes and modifications may be made therein within the purview of this invention as defined in 95 the appended claims.

Having described my invention what I claim as new and desire to secure by Letters Patent is:

1. A shoe buckle holder comprising means 105 for engaging the back bar of a buckle, clamp members for receiving the upper marginal edge of a shoe, a clamp lever for operating one of said clamp members, and prongs on the upper portion of said clamp lever for additionally engaging said back bar.

2. A shoe buckle holder comprising a front portion having a groove for receiving the back bar of a buckle, spaced projections stamped out of said front portion and overlying said groove for engaging the back bar, clamp members below said front portion and integral for receiving the upper marginal edge of a shoe, and a clamp lever pivotally supported behind said front portion for operating one 110 of said clamp members.

3. A shoe buckle holder comprising a front portion having a groove for receiving the back bar of a buckle, spaced projections stamped out of said front portion and overlying said groove for engaging the back bar, said projections being joined to the front portion on the same side of said groove, a slit in said front portion between said projections on the opposite side of said groove, a tongue 125

adjacent said slit and positioned behind said front portion, clamp members below said front portion and adapted to receive the upper marginal edge of a shoe, and a clamp lever behind said front portion adapted to simultaneously tighten said clamp members and to force said tongue through said slit.

4. A shoe buckle holder comprising a front portion and a pair of side portions, means on 10 said front portion for engaging the back bar of a buckle, clamp members for receiving the upper marginal edge of a shoe, and a clamp lever pivotally supported in said side portions for operating one of said clamp 15 members.

5. A shoe buckle holder comprising a front portion and a pair of side portions, means on 20 said front portion for engaging the back bar of a buckle, clamp members for receiving the upper marginal edge of a shoe, a clamp lever 25 pivotally supported in said side portions for operating one of said clamp members, and means on said clamp lever for additionally engaging said back bar.

6. A shoe buckle holder comprising a vertical front portion, vertically spaced projections stamped out of said front portion and extending across the face of the latter, a clamp member integral with the lower end of 30 said front portion, a second clamp member for cooperation with the first mentioned clamp member, and a clamp lever for operating said second clamp member.

7. A shoe buckle holder comprising a vertical front portion, vertically spaced projections stamped out of said front portion and extending across the face of the latter, said 35 projections being joined to the front portion adjacent one edge thereof, a slit in said front portion between said projections and adjacent the opposite edge of said front portion, a tongue positioned behind said slit, a clamp member integral with the lower end of said front portion, a second clamp member for 40 cooperation with the first mentioned clamp member, a clamp lever behind said front portion adapted to simultaneously operate said second clamp member and to force said tongue through said slit.

8. A shoe buckle holder comprising a vertical portion, means on said vertical portion for receiving the back bar of a buckle, clamp members integral with said vertical portion and adapted to engage the upper marginal 50 edge of a shoe, and a clamp lever for operating one of said clamp members.

9. A shoe buckle holder comprising a vertical portion, means on said vertical portion for receiving the back bar of a buckle, rearwardly extending side portions integral with 55 said front portion, a clamp member integral with the lower end of said vertical portion, a downwardly directed extension from the upper end of said vertical portion positioned between said side portions, said extension ter-

minating in a clamp member adapted to co-operate with the first mentioned clamp member, and a clamp lever pivotally supported in said side portions and adapted to bear against said extension for operating the second mentioned clamp member. 70

10. A shoe buckle holder comprising a vertical front portion having a groove for receiving the back bar of a buckle, vertically spaced projections stamped out of said front portion and overlying said groove for engaging the back bar, said projections being joined to the front portion on the same side of said groove, a slit in said front portion between said projections on the opposite side of 75 said groove, a clamp member integral with the lower end of said vertical portion, rearwardly extending side portions integral with said front portion, a downwardly directed extension from the upper end of said vertical portion positioned between said side portions, said extension terminating in a clamp member 80 adapted to co-operate with the first mentioned clamp member, a tongue integral with said extension and positioned behind said slit, a clamp lever pivotally supported in said side 85 portions and adapted to bear against said extension to thereby simultaneously operate the second mentioned clamp member and force said tongue through said slit, and means on 90 said clamp lever for additionally engaging said back bar. 95
